1 Claim

ABSTRACT OF THE DISCLOSURE

In a high-frequency ion source the discharge takes place between a secondary-emitting electrode and a grid between which a high-frequency field is set up and in which the secondary electrons return again to the electrode in one cycle.

The invention relates to an ion source, in which ions are formed in a high-frequency electric field.

In the known ion sources, the high-frequency discharge takes place in a space which has a higher pressure than the acceleration space because otherwise insufficient ions are formed. This necessitates the maintenance of a continuous gas flow from the ionization space to the acceleration space. This involves that in general only small ion extraction apertures can be used and that the efficiency of said ion sources is comparatively low.

It is the object of the invention to provide a more favourable arrangement.

According to the invention, in an ion source in which ions are formed in a high-frequency electric discharge, said electric discharge occurs between two electrodes one of which is secondary-emitting and the other of which is grid-like, the mutual distance, the amplitude and the frequency of the electric field being such that emitted secondary electrons again return to the secondary-emitting electrode after one cycle. In this arrangement the production takes place at one electrode and that independent of the gas pressure once the discharge in the gas has been ignited. The known arrangement requires a rather high gas pressure to maintain the discharge. In an arrangement according to the

2

invention, a pressure lower than, for example, 10^{-4} Torr is no objection for maintaining the electron production and therewith the ionisation of the gas.

In order that the invention may be readily carried into effect, it will now be described in greater detail, by way of example, with reference to the accompanying drawing, which diagrammatically shows a cross-sectional view of an electrode arrangement for an ion source according to the invention.

Referring now to the figure, reference numeral 1 denotes a hollow electrode, radius 12 cm., the surface of which consists of oxidized silver. 2 is a copper grid having wide meshes and arranged concentrically with 1, radius 9 cm. An extra electrode 3 is arranged in the centre of 1 and 2 and is supported by a quartz plate 4. An accelerating electrode is denoted by 5. In the space between the electrodes a deuterium-tritium mixture is provided at a pressure of 10^{-4} torr. An alternating voltage from source 6 of approximately 40 mc./s. and 150 v. amplitude is set up between the electrodes 1 and 2. Electrode 1 is 500 volts negative with respect to 2. 5 may be a few tens of kv. negative with respect to 3. Ions formed in the space between 1 and 2 are introduced into the accelerating space of electrode 5, through electrode 3. The arrangement is suitable for a neutron generator.

What is claimed is:

1. An ion source comprising two spaced electrodes defining a region filled with a gas forming ions during an electrical discharge; one of said electrodes being secondary-emitting and the other grid-like, and means to produce a high-frequency electric field between said electrodes having an amplitude and frequency such that emitted secondary electrons return again to the secondary-emitting electrode after one cycle.
